Primary Examiner—James Gandy*Assistant Examiner*—Robert M. Spear*Attorney, Agent, or Firm*—R. Reams Goodloe, Jr.**[57] CLAIM**

The ornamental design for a surface pattern for a tire sidewall, as shown and described.

DESCRIPTION

FIG. 1 is a perspective view of a surface pattern for a tire sidewall, showing my novel design; and,

FIG. 2 is a side elevational view of a surface pattern for a tire sidewall, showing my novel design.

The figures are lined to indicate the color gold. The broken line showing of a tire is for illustrative purposes only and forms no part of the claimed design.
